[57] ABSTRACT

A prefabricated wall section for use in swimming pool construction having a molded, glass fiber containing panel defining a facial section with reinforcing structure secured to the rear side thereof. The wall section includes an integral coping along the upper edge of the panel. The wall sections are preferably assembled end-to-end and anchored in concrete.

WALL SHELL CONSTRUCTION

BACKGROUND OF THE INVENTION

This invention relates to prefabricated wall sections and, more particularly, to wall sections having molded panels for use in constructing swimming pools. Further, this invention relates to an improvement in my U.S. Pat. No. 3,396,500, issued Aug. 13, 1968.

A technique for constructing swimming pools is explained generally in my aforementioned U.S. Pat. No. 3,396,500 and reference is made thereto by way of example. The present invention is directed to an improvement in the structure of prefabricated wall sections utilized in the construction of swimming pools.

It is an object of this invention to provide a prefabricated wall section for use in swimming pools, said section being of light weight construction which will remain in upright position without the use of a heavy brace during the installation of the pool.

It is a further object of this invention to provide a prefabricated wall section incorporating one or a plurality of integral structural reinforcing members which may be of a common shape regardless of the curvature of the particular panel to which they are attached.

It is a further object of this invention to rigidify the prefabricated wall sections in a manner which is less expensive than has been known heretofore and yet capable of accomodating differing expansion forces so that the wall section will not crack or separate from adjacent sections during abnormal temperature conditions.

It is a further object of this invention to provide a prefabricated swimming pool wall section which has a pre-formed integral coping along its upper edge, thus requiring a minimum of hand finishing of the concrete used to anchor the wall, said coping being eye-appealing around the upper periphery of the finished swimming pool.

Other objects and purposes of this invention will be apparent to persons acquainted with the fabrication and/or installation of swimming pool constructions of this general type upon reading the following specification and inspecting the accompanying drawings, in which:

FIG. 1 is a fragment of a sectional view of a wall section for use in a swimming pool construction, said section being taken along the line I—I in FIG. 2;

FIG. 2 is a sectional view taken along the line II—II in FIG. 1;

FIG. 3 is a sectional view taken along the line III—III in FIG. 2;

FIG. 4 is a sectional view of a modified panel construction taken along a line generally corresponding to the section line II—II in FIG. 1;

FIG. 5 is a sectional view taken along the line V—V in FIG. 4;

FIG. 6 is a sectional view taken along the line VI—VI in FIG. 4, but without any concrete or earth fill being shown in association therewith;

FIG. 7 is an oblique view of a fragment of the rear side of a modified wall section for use in a swimming pool construction;

FIG. 8 is a sectional view taken along a plane perpendicular to the wall section shown in FIG. 7, which plane contains the apex of the V-shaped reinforcing rib secured thereto; and

FIG. 9 is an enlarged fragmentary of still another modified wall section.

The words "up," "down," "right" and "left" will designate directions in the drawings to which reference is made. The words "front" and "rear" will refer to the inner and outer sides, respectively, of the swimming pool wall. Such terminology will include the words above specifically mentioned, derivatives thereof and words of similar import.

DETAILED DESCRIPTION

10 A prefabricated wall section 10, shown in FIG. 1, comprises a molded (thermo-formed) plastic (Acrylic) panel 11 having glass fibers therein having any desired shape, such as the shape specifically illustrated in FIGS. 1 and 2. It may also be flat. More specifically, the panel 11 is curved, as illustrated in FIG. 2, and terminates at its lower edge in a generally S-shaped anchor 12 which extends the full width of the panel. That is, the panel 11 is of thin-wall construction having a majority of both sides thereof generally vertically aligned. The S-shaped anchor 12 includes a first flange 13 which is secured to the bottom edge of the panel 12 and extends rearwardly therefrom. The anchor 12 also has a leg 14 which extends downwardly from the rearward edge of the flange 13 and, finally, a flange 15 extends rearwardly from the bottom edge of the leg 14.

15 The upper portion of the panel 11 is formed to define a concavity 16 on the rearward side thereof thus forming a decorative convex coping 17 on the front surface thereof which projects frontwardly from the front surface of the panel 11. The coping 17 projects rearwardly and has a horizontal section 18 which extends rearwardly to a point approximately directly above the rear edge of the flange 15 of the S-shaped anchor 12.

20 A pair of end walls 21 and 22 are provided on the opposite end edges of the panel 11 and extend rearwardly therefrom as best illustrated in FIG. 2. Thus, the upper wall 18, the anchor 12 and the end walls 21 and 22 combine with the panel 11 to define a boxlike receptacle which opens rearwardly.

25 The panel is thereafter coated on its rear surface with a fiberglass impregnated resin to provide a fiberglass coating 33. The acrylic material of the panel forms a smooth, hard and nonyellowing surface on the front of the panel 11.

30 A plurality of ribs 23 are thereafter provided in the coated receptacle and extend between the flange 13 of the S-shaped anchor 12 and the wall 18 at the upper end of the panel 11. Each rib 23 is composed of an elongated and rigid element of urethane material 24 which is adhesively secured at 26 to the rear surface 27 of the panel 11. The upper end of the urethane element or rail 24 is enlarged as at 28 (FIG. 1) and the enlargement is received in the concavity 16 defined by the coping 17 at the upper end of the panel 11. The spacing and thicknesses of the urethane rails 24 can be varied as desired, depending upon strength requirements, and they may be integrally molded with the panel 11, as may the end walls 21 and 22. Generally, the urethane rails are identical in shape and, if more stiffening is required for the panel 11, the additional urethane rails may be augmented as discussed hereinafter.

35

40 A protuberance 29 is provided along the rear edge of each of the urethane rails 29 preferably near the upper end thereof and has an opening 31 therethrough. An elongated steel rod 32 is received through each of the openings 31 and preferably extends continuously along the panel 11, as illustrated in FIG. 2.

If desired, the panel 11 may have a plurality of elongated recesses 35 molded therein to imitate a ceramic tile in appearance immediately beneath the coping 17, as illustrated in FIG. 1.

The prefabricated wall section 10 described hereinabove is utilized in the following manner during the construction of a swimming pool. A plurality of wall sections 10 are placed end-to-end to define the peripheral shape of the pool. The S-shaped anchor 12 on each of the prefabricated panels 10 is urged into the fresh concrete floor 36 adjacent the periphery thereof so that the concrete engages the lower edge of the vertical surface of the acrylic panel 11 as illustrated in FIG. 1. The concrete floor 36 is then made smooth by hand and then permitted to harden. Earth fill or other like solid construction material is then pushed gently into engagement with the rear surface of each of the prefabricated wall sections 10 leaving a pocket adjacent the upper end of the wall wherein the steel rod 32 is yet exposed. Thereafter, a concrete deck 39 is poured so that the upper surface 41 thereof is flush with the upper surface of the rearward extension 18 of the coping 17. The concrete poured into the pocket 38 will embed the steel rod therein and serve to further strengthen and rigidify the upper portion of the prefabricated wall section 10. Concrete also enters into the concavity 16 between the ribs 23.

ALTERNATE CONSTRUCTIONS

(FIGS. 4 to 9)

Parts of the prefabricated wall section 10A (FIGS. 4, 5 and 6) will be referred to by the same reference numerals designating corresponding components of the wall section 10 but with the suffix "A" added thereto. The wall section 10A is composed of a molded (thermo-formed) plastic (Acrylic) and fiberglass impregnated panel 11A which may be identical in shape to the panel 11 discussed hereinabove. The difference between the wall 10A illustrated in FIG. 4 and the wall 10 illustrated in FIG. 1 is that each of the ribs 23A is integral with the urethane material 40 which defines a rail filling the concavity 16A (FIG. 5). The rear surface of the panel 11A is coated with a fiberglass impregnated resin to provide a coating 33A. Thereafter, each of the urethane ribs 23A and the urethane rail 40 interconnecting the upper ends of the ribs as illustrated in FIG. 5, is adhesively secured to the rear surface of the panel 11A.

In the embodiment illustrated in FIG. 5, a relatively wide recess 42 is molded into the panel 11A for reception of a plurality of ceramic tiles 43 which may be secured therein by an adhesive at the completion of the installation of the wall section 10A in the swimming pool construction.

A protuberance 29A is provided on the rear edge of each of the ribs 23A and has an opening therethrough for receiving a steel rod 32A. The installation of the wall sections 10A to form a swimming pool is generally the same as discussed above with respect to the wall sections 10.

Although particular preferred embodiments of the invention have been disclosed in detail for illustrative purposes, it will be recognized that variations or modifications of the disclosed apparatus including the rearrangement of parts, lie within the scope of the present invention.

The embodiments of the invention in which an exclusive property or privilege is claimed are defined as follows:

1. A wall construction for a swimming pool, comprising:

a molded plastic and fiberglass wall section having an open boxlike configuration, said wall section having an enlarged bottom panel which is normally disposed in a substantially vertical orientation, the outer surface of said bottom panel comprising the front side of said wall section; said wall section including a coping integrally formed with and extending along the upper edge of said panel, said wall section also including an anchoring flange integral with and extending along the lower edge of said panel, said coping and said anchoring flange each projecting rearwardly of said panel; said wall section further including a pair of end walls integral with and extending along the opposite vertical edges of said panel, said end walls projecting rearwardly from said panel and extending vertically between said coping and said anchoring flange; a plurality of upright and substantially parallel reinforcing ribs fixedly secured to said wall section, said ribs being laterally spaced from one another and fixedly secured to the rear surface of said panel, each of said ribs being relatively narrow and occupying a relatively minor part of said rear surface;

each of said ribs having an opening extending therethrough perpendicular to the elongated length of said rib, said opening extending in a direction substantially parallel with said rear surface, the openings as formed in said plurality of ribs being substantially aligned; and

elongated rigid rod means received within said plurality of openings and extending between said plurality of ribs, said rod means being spaced rearwardly of said rear surface, whereby said rod means is adapted to be embedded within concrete or the like when said wall construction is installed.

2. A wall construction for a swimming pool, comprising:

a molded plastic and fiberglass wall section having an open boxlike configuration, said wall section having an enlarged bottom panel which is normally disposed in a substantially vertical orientation, the outer surface of said bottom panel comprising the front side of said wall section;

said wall section including a coping integrally formed with and extending along the upper edge of said panel, said wall section also including an anchoring flange integral with and extending along the lower edge of said panel, said anchoring flange projecting rearwardly of said panel;

said coping including a projecting portion which is fixed to and extends along the upper edge of said panel and projects forwardly from the outer surface of said panel, said coping also having a substantially horizontal flange portion which is integrally connected with the upper end of said projecting portion, said horizontal flange portion projecting rearwardly beyond the rear surface of said panel;

said wall section further including a pair of end walls integral with and extending along the opposite vertical edges of said panel, said end walls projecting

rearwardly from said panel and extending vertically between said coping and said anchoring flange; and a plurality of upright and substantially parallel reinforcing ribs fixedly secured to said wall section, said ribs being laterally spaced from one another and fixedly secured to the rear surface of said panel, each of said ribs being relatively narrow and occupying a relatively minor part of said rear surface, and said ribs being formed with an enlarged portion on the upper end thereof projecting into and filling the cavity defined by said projecting portion.

3. A wall construction according to claim 2, wherein said ribs are constructed of a rigid plastic material and extend throughout the height of said panel from the horizontal flange portion of said coping to said anchoring flange.

4. A wall construction according to claim 2, including an elongated rail constructed of a rigid plastic material and positioned within the cavity defined by said projecting portion, said rail extending longitudinally of said cavity and substantially filling same, said rail being fixedly connected to said plurality of spaced ribs.

5. A wall construction according to claim 2, wherein said panel has a pair of vertically spaced grooves adja-

cent the bottom wall of said swimming pool; and a liner having a rib and a seal adjacent the upper edge thereof, each being received in one of said grooves.

6. A wall construction according to claim 2, wherein a plurality of said wall sections are arranged laterally adjacent one another to define the peripheral shape of a pool, the rearward surface of said panels being mounted against and buttressed by concrete, earth fill or like solid construction materials; and

10 at least one rigid rod coacting with said wall sections and embedded in said solid construction material buttressing said one side of said panels to structurally reinforce the pool construction.

7. A wall construction according to claim 6, wherein each said rib has an opening extending therethrough in a direction substantially perpendicular to the longitudinal length of said rib, the openings as formed in said plurality of ribs being substantially aligned, and said rigid rod extending through said plurality of openings and being supported on and interconnecting said plurality of ribs, said rigid rod being disposed substantially parallel with but spaced rearwardly from the rear surface of said panel.
